UNITED STATES PATENT OFFICE.

HARRY R. WADE, OF TOLEDO, OHIO, ASSIGNOR TO J. W. HUGHES.

SAFETY-RAZOR.

1,000,059.

Specification of Letters Patent. Patented Aug. 8, 1911.

Application filed January 5, 1910. Serial No. 586,551.

To all whom it may concern:

Be it known that I, HARRY R. WADE, a citizen of the United States, residing at Toledo, in the county of Lucas and State of Ohio, have invented new and useful Improvements in Safety-Razors, of which the following is a specification.

This invention relates to certain new and useful improvements in safety razors, and the object of the invention is to provide a simple, novel, and inexpensive device of this character which can be instantly adjusted, with respect to the handle, to various positions, adapting the razor to right and left hand usage with ease and facility.

A further object of the invention is to reduce the number of parts, and to simplify such parts to a minimum extent, while yet maintaining a maximum degree of efficiency required of a device of this type.

Still further the invention aims to provide means of simple character for allowing the removal and replacement of the blades which will be easily and quickly operable, and which will positively and securely hold the blade in its normal position.

Further and other objects will be later set forth and of themselves manifested.

In the drawings:—Figure 1 is a rear elevation of the invention, Figs. 2, 3, 4 and 5 are similar views showing the device adjusted in different positions for varying uses required in a shaving operation, Fig. 6 is a front elevation of the device, Fig. 7 is a section taken on line 7—7 of Fig. 1 and Fig. 8 is a similar view taken on line 8—8 of Fig. 1.

The invention includes a base plate 1 which is formed at one end with ears 2, 2, these ears being arranged in spaced relation as shown in the drawings. A locking bar 3 is provided at one end with a perforated ear 4 which is received between the ears 2, 2, a pin 16 as shown in Fig. 8 being passed through the openings in the ears 2, 2, and 4 whereby a hinge connection is formed between the locking bar 3 and the base plate 1. The opposite end of the locking bar 3 is formed with a catch member 5 which is adapted to snap or spring over the opposite end of base plate 1. Lugs or protuberances 17 are formed on the last named end of base plate 1, and engage the opposite ends of the catch member 5, thus holding the latter in immovable position in a lateral direction,

and also serving as guides when the catch member 5 is being sprung or moved into position.

The base member 1 is formed at its lower end with a guard 6 and is further formed with end lugs 15, the function of which is to engage the opposite end of the cutting blade 14, the inner end of which blade 14 is also engaged by stops 20 as shown in Fig. 6. It will thus be apparent that the stops 20, 20, and the guide lugs 15, 15, serve to position the blade 14 with relation to the base plate 1, maintaining the same in proper alignment to allow the locking bar 3 to be snapped into position, it being understood that the blade 14 is thereby clamped between the locking bar 3 and the base plate 1.

The base plate 1 is formed on its rear face with a plurality of indentures or depressions 12, the number of indentures depending upon the number of different positions which the handle is to be capable of being adjusted to. In the present case five of such indentures or depressions 12 have been illustrated. Adapted to be snapped or sprung into the indentures 12 is a teat or projection 11 carried by the handle bearing arm 9 and formed thereon by bending out a small part of the metal at the outer end wall formed by a longitudinal slot 18 in one end of arm 9 as clearly illustrated in Fig. 7. A screw or rivet 13 passes through the arm 9 at a point at the inner end of slot 18, the screw or rivet being secured to base plate 1 thereby pivotally uniting the arm 9 to such base plate.

In order to provide a spring-like action for the teat 11, whereby the latter is resiliently held in any one of the depressions 12, the slotted end of arm 9 is bowed or arched upwardly as depicted in Fig. 7, the outermost or free end of arm 9 being given a slight upward bend or inclination as at 20' in order to provide a seat for the thumb of the user's hand in adjusting the arm to its various positions. The inner end of arm 9 is likewise given an upward inclination and is formed with a split spring sleeve 8 adapted to frictionally hold and clamp the inner end of the handle member 7.

By inspection of Figs. 1 to 5 of the drawings, it will be observed that the handle member 7 can be adjusted to five different positions, Fig. 5 showing the device adapted for left hand use, Fig. 4 depicting the de-

vice in position for right hand use, while Figs. 1, 2 and 3 illustrate the device adapted for use with either the right or left hand. It will further be seen that the device is 5 literally constituted of but two parts, namely the holder and the blade which is a desideratum in a device of this particular type.

What is claimed as new is:

- 10 1. In a safety razor, a holder including a base plate formed with a plurality of indentures, a spring handle carrying member pivoted to the base plate, and formed with a bowed portion and a longitudinal slot which 15 extends through the bowed portion, the metal at the outer end wall formed by said slot being bent outwardly to form a teat adapted to project in one of said indentures, and means for securing a blade to said base plate.
- 20 2. A safety razor including a base plate, spaced ears on one end of the base plate, a locking bar, an ear on one end of the locking bar received in said space between the first named ears, a pin passed through 25 all of said ears whereby the locking bar is hingedly related to the base plate, a catch member on the opposite end of said locking bar adapted to snap over the opposite end of the base plate, and guide lugs on the last

named end of the base plate adapted to engage the catch member.

3. In a safety razor, a holder including a base plate formed with a plurality of depressions, an arm formed of spring metal and pivoted to said base plate, said arm having a struck out portion beyond its pivotal point at its free end to form a teat to engage in said depressions, said arm having a bowed portion between its free end and its pivotal point to provide a resilient mounting for the teat.

4. In a safety razor, in combination with a holder including a substantially flat base plate, formed with a series of depressions, an arm pivoted to the base plate and having its outer free end provided with a teat to enter one of the depressions, said outer end of the arm being resilient to allow said teat to be moved from one depression to another by a mere partial rotating movement of the 50 arm.

In testimony whereof I have hereunto set my hand in presence of two subscribing witnesses.

HARRY R. WADE
